LOADING MACHINE

William W. Sloane, Chicago, Ill., assignor to
 Goodman Manufacturing Company, Chicago,
 Ill., a corporation of Illinois

Application July 2, 1936, Serial No. 88,525

5 Claims. (Cl. 198—8)

This invention relates to improvements in loading machines of the type adapted to gather and load material such as coal from the ground and more particularly to gathering heads including gathering chains having flights extending therefrom for initially picking up the material and loading it onto a flight conveyer for discharge in a mine car or the like.

More specifically, my present invention is an improvement in the general form of gathering head described in a prior application, Serial No. 50,861, filed by Frank Cartlidge, November 21, 1935.

Among the objects of my present invention is to provide a simpler and more efficient construction of loading head especially arranged to take up a minimum amount of vertical height and provide ample vertical clearance between the under side of the flight conveyer and the ground without increasing the distance material must be moved to be discharged onto the flight conveyer.

Another object of my invention is to provide an improved form of power drive to the gathering chains independent of the flight conveyer which permits the use of a relatively large drive sprocket for driving the gathering chains and permits the flight conveyer to turn about a relatively small direction changing device at its forward end and thus effects an arrangement whereby the flight conveyer may extend closely adjacent to the ground in an inclined plane without decreasing the vertical clearance between the under side of said conveyer and the ground, and thus permitting the gathering head to operate efficiently where the bottom is uneven.

Other objects of my invention will appear from time to time as the following specification proceeds.

40 My invention may be more clearly understood with reference to the accompanying drawings wherein:

Figure 1 is a side elevation, with certain parts broken away and shown in section, of the front portion of a loading machine, illustrating one form in which my invention may be embodied;

Figure 2 is a plan view of the front portion of the loading machine shown in Figure 1, with certain parts broken away and in section in order to more clearly illustrate certain details of my invention not shown in Figure 1;

Figure 3 is an enlarged transverse sectional view taken through the drive end of one of the gathering mechanisms;

55 Figure 4 is an enlarged partial fragmentary

view of the front portion of the gathering element, shown in longitudinal section, in order to more clearly illustrate certain details of my invention;

Figure 5 is a fragmentary transverse sectional view taken substantially along lines 5—5 of Figure 1;

Figure 6 is an enlarged fragmentary transverse sectional view taken substantially along lines 6—6 of Figure 1; and

Figure 7 is an enlarged fragmentary transverse sectional view taken substantially along lines 7—7 of Figure 4.

In the drawings my invention is shown as being embodied in a loading machine of the track mounted type, the main elements of which are essentially the same as shown in a prior patent to Frank Cartlidge, No. 2,066,137. The gathering and loading element is mounted at the forward end of an inclined elevating conveyer 10, which as usual is carried at the forward end of a mobile truck having suitable power operating and controlling devices, which need not be shown or described in detail herein as the present invention is directed particularly to the construction of the gathering and loading element and power drive therefor.

The elevating conveyer 10 includes a trough-like conveyer frame section 11 and a forward gathering section 12 connected thereto in a suitable manner, which gathering section has an apron 14 extending laterally along opposite sides of the conveyer and forwardly across the forward end thereof to the ground so that the forward end of said apron may engage the ground.

The conveyer section 11 includes a plate 15 extending therealong which forms a surface along which material may be moved by transversely extending flights 16, 16 carried between suitable parallel spaced endless chains 17, 17 at intervals 30 therealong.

The conveyer section 11 also has a pair of upright side plates, 24, 24 which define the main body of the conveyer trough and extend downwardly beneath the bottom plate 15 to provide a support means for the moving parts of the conveyer and for the drive means for the gathering mechanism in a manner which will hereinafter more clearly appear as this specification proceeds. Said side plates are also flared outwardly 50 at opposite sides of said conveyer section to form a trough-like frame along which material may be moved, as indicated in Figures 1, 2 and 6.

The endless chains 17, 17 are trained around sprockets 18, 18 on a transverse shaft 19, disposed 55

at the rearward end of the conveyer section 11 and forming a drive member for said endless chains (see Figures 2 and 5). From the sprockets 18, 18 said endless chains extend downwardly along the conveyer frame 11 beneath the plate 15 to and around direction changing devices 20, 20. Said direction changing devices are herein preferably shown as being rollers mounted on the inner ends of stub shafts 21, 21 journaled in bearing housings 22, 22 in a suitable manner, which housings are secured to and extend outwardly from the side plates 24, 24 of the conveyer section 11 adjacent the forward end thereof (see Figure 7). The diameter of said rollers has been reduced to the minimum dimensions necessary to permit reversal in movement of said endless chains, to permit their disposal closely adjacent the forward end of the frame 11 without decreasing vertical clearance between the forward end of said conveyer and the ground. From the direction changing members 20, 20, said endless chains extend upwardly along the upper surface of the plate 15 on wearing strips 23, 23 disposed along opposite sides of said plate as is best shown in Figures 1 and 6.

Immediately in front of the rollers 20, 20 is a curved plate 25 conforming to the form of the chains 17, 17 as they round said rollers, and terminating at the delivery edge of the apron 14, which edge is herein shown as being forwardly of the stub shafts 21, 21 and the forward end of the plate 15, in order to minimize the distance material must be moved along said apron.

An inclined bottom plate 29 extends upwardly from the forward end of the apron 14 beneath the endless chains 17, 17, and its forward end terminates at the forward end of said apron. Said plate together with the forward end of said apron serves as a shoe on which the forward end of the gathering and loading element may rest. Said plate also is so arranged as to be inclined upwardly with respect to the ground at an angle sufficient to permit ample clearance between the ground, and afford an arrangement whereby the gathering head may readily be manipulated over an irregular mine bottom.

The means for gathering material and moving it onto the conveyer includes a pair of endless chains 30, 30 movable along chain guides 31, 31. Said chain guides are mounted on the upper surface of the apron 14 and extend along opposite sides of the conveyer from a point disposed forwardly of the forward end thereof. Gathering flights or arms 33, 33 extend laterally from said endless chains at suitable intervals therealong. Each gathering arm is pivotally mounted on a link of its respective endless chain, for upward swinging movement, between projecting lugs 34, 34 on a pivotal pin 35. Said arms may thus be raised as they approach their turning point away from the conveyer to aid in clearing them from material on the conveyer and permit material to be taken away from them at a faster rate of speed than their speed of travel. The means for releasing or clearing the material on the conveyer from the gathering arms as they approach their upward turning point will only herein be described briefly since it is clearly shown and described in the aforementioned application of Frank Cartlidge, and includes a lifting cam 36 which extends along the inside of each chain guiding member 31 from a point adjacent the forward end of the conveyer to and partially around the point where the gathering arms turn away from the conveyer.

Said lifting cam is adapted to engage a heel 37 of each gathering arm so as to raise each arm gradually to a maximum as it passes around its rearward turning point. A semi-frusto-conical supporting surface 38 is provided which has an inner edge substantially in line with the upper end of the cam 36, and extends inwardly around the rearward turning point of said arms to form a support for said arms after they leave said lifting cam. From thence, the outer margins of said engaging surface bend downwardly toward the apron 14 to permit said arms to rest on said apron.

Rollers 39, 39 are provided at the forward end of each chain guiding member 30 to positively guide the gathering arms in a plane parallel to the apron 14 and form direction changing devices about which the endless chains turn. Each roller is provided with spaced flanges 40 and 41 adapted to engage each gathering arm above and below the pivotal axis thereof to hold said gathering arms from upward or downward movement at their forward turning point.

The endless gathering chains 30, 30 are trained around drive sprockets 43, 43 at their upper turning point, each of which sprockets is keyed on a shaft 44 disposed perpendicularly to the plane surface of said apron (see Figure 3). The upper end of said shaft is journaled in the chain guide member 31 on an anti-friction bearing 45 mounted in the chain guiding member 31, while the lower portion of said shaft is journaled in an anti-friction bearing member 46 mounted in a housing and bearing support member 47 secured to the under side of the apron 14 and side 24 of the conveyer frame 11. A bevel gear 48 is keyed on the lower end of the shaft 44 and meshes with and is driven from a bevel pinion 49 keyed on a transversely disposed stub shaft 50 journaled in the housing and bearing support member 47 in suitable anti-friction bearings. A sprocket 51, the diameter of which is considerably greater than the diameter of the roller 20, is keyed on the inner end of said shaft and meshes with and is driven from an endless drive chain 52 extending rearwardly along the side plate 24.

With reference now in particular to the novel form of drive connection to the endless drive chains 55, 55 and the gathering chains 30, 30, which includes the sprockets 51, 51, a sprocket 54 is keyed on the outer end of the transverse drive shaft 19 (see Figures 1, 2 and 5). Said sprocket meshes with a drive chain 55 which extends forwardly along one side of the conveyer and meshes with and drives a sprocket 56 herein shown as being splined on the end of the transversely disposed shaft 59. Said shaft is journaled in the conveyer frame 11 on suitable anti-friction bearings mounted in housings and bearing support members 60 and 61 extending laterally from respective sides 24, 24 of the conveyer frame 11, and secured thereto. Sprockets 62, 62 are mounted on said transverse shaft adjacent opposite sides of the conveyer frame 11 for rotation with said shaft and mesh with the endless drive chains 52, 52 for driving said chains (see Figure 6).

It will be apparent from the foregoing that a simplified drive has been provided for the gathering chains which is independent of the conveyer, but is driven from the shaft which drives the conveyer, and which is so arranged as to relieve the conveyer of the burden of driving the driving chains and thus permit the use of a relatively small direction changing device at the forward

end of the conveyer and permit the gathering chains to be driven from relatively large sprockets. This construction permits the use of a relatively straight conveyer without increasing the distance material must be moved along the apron 5 to be discharged onto the conveyer and permits said conveyer to be disposed closely adjacent the forward end of the conveyer section 11 without decreasing clearance between the bottom 10 plate 29 and the ground.

While I have herein shown and described one form in which my invention may be embodied, it will be understood that the construction thereof and the arrangement of the various parts may be altered without departing from the spirit and scope thereof. Furthermore, I do not wish to be construed as limiting myself to the specific embodiment illustrated, excepting as it may be limited in the appended claims.

20 I claim as my invention:

1. In a loading machine, an elevating conveyer including an inclined frame, an apron extending along each side of said conveyer and across the forward end thereof and forwardly therefrom to the ground, gathering means movable along said apron and extending along each side of said conveyer and including a pair of spaced gathering chains having gathering flights projecting laterally therefrom, said conveyer including a pair of 25 spaced endless chains having flights spaced therebetween, and extending from a drive shaft at the rearward end of said frame downwardly therealong to and around direction changing devices of a relatively small diameter at the forward end 30 of said frame, and said drive to said gathering chains including a pair of parallel spaced endless chains extending parallel to said conveyer chains and driven from said drive shaft, said chains being trained around drive sprockets at the forward end of their path of travel which are of a larger 35 diameter than the diameter of said direction changing devices and said sprockets extending above the lower run of said conveyer and being each mounted on an individual shaft journaled 40 outside of the lateral limits of said conveyer.

45 2. In a loading machine, a frame having an endless flight conveyer movable therealong and trained around coaxial direction changing devices at the forward end thereof, an apron extending along each side of said conveyer, across the forward end thereof, and forwardly therefrom and having a forward end adapted to engage the ground, gathering means movable along said apron and extending along each side of said 50 conveyer including a pair of spaced gathering chains having flights extending laterally therefrom, a shaft disposed at the rearward end of said frame for driving said flight conveyer, and a drive connection from said shaft independent of said flight conveyer for driving said gathering chains including a shaft mounted in said frame parallel to said transverse shaft and spaced forwardly therefrom, a drive connection between said shafts, and drive connections from opposite 55 ends of said second-mentioned shaft to said gathering chains including sprockets having geared drive connections with said gathering chains, the diameter of which sprockets is greater than the diameter of said direction changing devices.

60 3. In a loading machine, a frame having an endless flight conveyer movable therealong and trained around coaxial direction changing devices at the forward end thereof, an apron extending along each side of said conveyer, across the forward end thereof, and forwardly there-

from and having a forward end adapted to engage the ground, gathering means movable along said apron and extending along each side of said conveyer including a pair of spaced gathering chains having flights extending laterally therefrom, a shaft disposed at the rearward end of said frame for driving said flight conveyer, and a drive connection from said shaft independent of said flight conveyer for driving said gathering chains including a shaft mounted in said frame parallel to said transverse shaft and spaced forwardly therefrom, a drive connection between said shafts including a chain and sprocket drive, and drive connections from opposite ends of said second-mentioned shaft to said gathering chains including a chain and sprocket drive extending along each side of said frame having geared drive connections with said gathering chains, the diameter of the sprockets of said drives being greater than the diameter of said 10 direction changing devices.

4. In a loading machine, an inclined frame having an endless flight conveyer movable therealong, a direction changing member about which said conveyer turns at the forward end of said frame, an inclined apron extending along each side of said conveyer and forwardly therefrom and having a discharge edge at the forward end of said conveyer and being adapted to engage the ground at its forward end, gathering means 25 movable along said apron and extending along each side of said conveyer including a pair of spaced endless chains having flights extending laterally therefrom, a shoe disposed beneath said apron and conveyer and extending rearwardly 30 and upwardly from the forward end of said apron, and the direction changing member about which said conveyer turns being of the minimum diameter requisite to reverse the direction of movement of said conveyer chain along said frame to 35 permit vertical clearance between said shoe and the ground, a drive connection for said flight conveyer including a transverse shaft at the rearward end of said frame, and means for driving said gathering chains arranged to maintain the 40 minimum dimensions of said direction changing member and distance material must be moved along said apron for discharge onto said conveyer including a drive connection from said shaft independent of said flight conveyer including a pair of sprockets having geared drive connection to said gathering chains, the diameter of which is greater than the diameter of 45 said direction changing device.

5. In a loading machine, an inclined frame having an endless flight conveyer movable therealong, a direction changing member about which said conveyer turns at the forward end of said frame, an inclined apron extending along each side of said conveyer and forwardly therefrom and having a discharge edge at the forward end of said conveyer and being adapted to engage the ground at its forward end, gathering means 55 movable along said apron and extending along each side of said conveyer including a pair of spaced endless chains having flights extending laterally therefrom, a shoe disposed beneath said apron and conveyer and extending angularly upwardly and rearwardly from the forward end of 60 said apron, and the direction changing member about which said conveyer turns being of the minimum diameter requisite to reverse the direction of movement of said conveyer chain along said frame to 65 permit vertical clearance be- 70

tween said shoe and the ground, a drive connection for said flight conveyer including a transverse shaft at the rearward end of said frame, and means for driving said gathering chains arranged to maintain the minimum dimensions of said direction changing member and distance material must be moved along said apron for discharge onto said conveyer including a shaft mounted in said frame parallel to said transverse shaft and spaced forwardly therefrom, a drive

connection between said shafts, and drive connections from opposite ends of said second-mentioned shaft to said gathering chains including forwardly disposed individual drive shafts journaled outside of the lateral limits of said conveyer and having sprockets of a greater diameter than said direction changing member mounted thereon, said sprockets extending above the bottom of said conveyer. 5

WILLIAM W. SLOANE. 10
